(57) **CLAIM**

The ornamental design for an assembled battery, as shown and described.

DESCRIPTION

FIG. 1 is a front perspective view of assembled battery showing our new design;

FIG. 2 is a top view thereof;

FIG. 3 is a front view thereof;

FIG. 4 is a bottom view thereof;

FIG. 5 is a back view thereof;

FIG. 6 is a right side view thereof;

FIG. 7 is a left side view thereof;

FIG. 8 is a top view that shows state of removing the top cover;

FIG. 9 is a sectional view taken along 9—9 of FIG. 3;

FIG. 10 is a sectional view taken along 10—10 of FIG. 3; and,

FIG. 11 is a sectional view taken along 11—11 of FIG. 6.

The broken line showing of environmental structure is for the purpose of illustrating and forms no part of the claimed design.
